REFRIGERANT FLOW CONTROLLING
MEANS

Franklyn Y. Carter, Detroit, Mich., assignor to
Detroit Lubricator Company, Detroit, Mich., a
corporation of Michigan

Application April 10, 1944, Serial No. 530,263

8 Claims. (Cl. 62—8)

1

This application relates to new and useful improvements in refrigerating apparatus, and more particularly to a system having a multi-pass evaporator and means for supplying refrigerant thereto.

An object of the invention is to provide a novel refrigerant distributor which will feed refrigerant equally to each of the passes or tubes of the evaporator.

Another object is to provide a distributor in which the probability of feeding any vaporized refrigerant to the distributor orifices is reduced to a minimum.

Another object is to provide means for accurately metering the flow of refrigerant to a multi-pass evaporator so as to maintain the same refrigerated to a substantially fixed extent during compressor operation.

Another object is to provide a photo-electric control for the feeding of refrigerant to the evaporator.

The invention consists in the improved construction and combination of parts and their cooperative relation to be more fully described hereinafter and the novelty of which will be particularly pointed out and distinctly claimed.

In the accompanying drawings to be taken as a part of this specification, there are fully and clearly illustrated several preferred embodiments of the invention, in which drawings:

Figure 1 is a diagrammatic view of a refrigerating apparatus showing the electrically controlled refrigerant distributor in longitudinal vertical section and showing the wiring diagram for the photocell control of the distributor, and

Fig. 2 is a diagrammatic view of part of the refrigerating apparatus of Fig. 1 but showing differential temperature responsive means for controlling the distributor.

In the accompanying drawings to be taken as a part of this specification, there are fully and clearly illustrated several preferred embodiments of the invention, in which drawings:

Figure 1 is a diagrammatic view of a refrigerating apparatus showing the electrically controlled refrigerant distributor in longitudinal vertical section and showing the wiring diagram for the photocell control of the distributor, and

Fig. 2 is a diagrammatic view of part of the refrigerating apparatus of Fig. 1 but showing differential temperature responsive means for controlling the distributor.

Referring to the accompanying drawing, 1 designates generally a motor driven compressor having an outlet conduit 2 connected to a re-

2

frigerant condenser 3 which feeds through a conduit 4 into a refrigerant receiver 5 from which a liquid line or conduit 6 connects to the inlet passageway 7 of the electric distributor 8. The bottom wall of the distributor 8 is formed by a closure plate or member 9 having a plurality of passageways 10 therethrough equal in number to the passes or tubes of the evaporator to be supplied with refrigerant. Each of the passageways 10 has secured and sealed therein a capillary refrigerant feeding tube 11 which has its other end connected to the inlet of one of the tubes or passes 12 of the multi-tube evaporator 13, having the usual suction header 14. The inlet 15 of the compressor 1 is connected to the suction header by a suction conduit 15 having intercalculated therein a light transmitting or bull's-eye portion 16 for the passage of a light beam therethrough from a light source 17 which may be the usual electric lighting device forming part of a photo-electric control system.

The distributor 8 has a vertical tubular hollow housing 18 with upper and lower end flanges 19, 20 respectively. Adjacent the upper end of 25 the housing member 18 there is an internal horizontal partition 21 which divides the housing member into an upper liquid inlet chamber 22 and a lower refrigerant feeding chamber 23. The inlet passageway 7 opens laterally into the chamber 22 which is communicatively connected to the chamber 23 by a valve port 24 in and extending vertically through the central portion of the partition 21. The top of the chamber 22 is closed and sealed by a casing 25 which is 30 clamped by bolts 26 to the flange 19. Within the casing 25 there is an electro-magnetic coil 27 surrounding a tubular guide member 28 in which there is reciprocally positioned the stem 29 of a valve member 30 cooperable with the port 35 24 to control flow therethrough. The valve member 30 carries an armature 31 for cooperation with the coil 27 to open the valve member 30. A light coil spring 32 may be provided within the guide member 28 to urge the valve member toward closed position. The bottom closure member 9 preferably has a flange 33 between which and the flange 20 a sealing gasket or the like 34 may be clamped by bolts 35. The chamber face of the closure member 9 is provided 40 with a cylindrical recess 36 to receive an orifice plate 37 having calibrated orifices 38 there through equal in number to the outlet passageways 10 and registering therewith. The side portions of the recess 36 extend laterally outward beneath the wall of the housing member 18 so

that the plate 37 will be tightly clamped by the bolts 35 in position between the closure member 9 and the housing member 18.

Each of the tubes 11 and its restricting orifice 38 has a predetermined resistance to refrigerant flow for a given compressor suction pressure and a given refrigerant pressure in the feeding chamber 23 for a given load on the evaporator 13. The valve port 24 is therefore made sufficiently large so that in the wide open position of the valve member 30, the effective flow area through the port 24 will cause a minimum drop of pressure from the liquid head pressure in the inlet chamber 22 and the pressure in the feeding chamber 23. By reason of the predetermined restriction to flow afforded by the orifices 38 and tubes 11, the pressure drop across the port 24 may be restricted to several pounds so that the pressure drop across the port 24 will not lower the pressure below or appreciably below a pressure corresponding to the saturation temperature of the liquid refrigerant supplied to the inlet chamber 22. The condenser 3, as is common in the refrigeration art, will cool the refrigerant somewhat below its saturation temperature as a factor of safety to eliminate gasifying of the refrigerant during its flow or passage through the liquid supply line 6. It is this usual cooling of the refrigerant below its saturation temperature which makes possible the discharge into the feeding chamber 23 of liquid refrigerant with little or no vaporization due to the small pressure drop through the valve port 24. The effective flow area of the port 24 is greater than the combined flow areas of the orifices 38 so that substantially instantaneously with the opening of the quickly acting valve member 30, the feeding chamber 23 will be filled solid with liquid refrigerant and no vaporization of the liquid refrigerant in the chamber 23 will occur. The size or volumetric capacity of the chamber 23 is sufficiently large so that during operation of the compressor 1 there will always be liquid refrigerant overlying the orifices 38 with the result that liquid refrigerant will be fed to the feeding tubes 11 and therefore the refrigerant will be equally and uniformly distributed to each of the passes or tubes 12 of the evaporator 13.

The valve member 30 is controlled by the magnet coil 27 which is in turn controlled by a relay switch 39 having its relay coil 40 in the electrical network of a photocell system including the light source 17. The light beam indicated by the dash dot line 41 from the source 17 shines through the transparent suction conduit section 16 and when not refracted by liquid refrigerant, the light beam passes through an aperture 42 in a shield or box 43 containing a photo-electric cell 44 and impinges upon the cathode 45. Energization of the cell 44 by the light shining upon the cathode 44 renders the control grid 46 of the electron tube 47 sufficiently positive so that current flow through the tube 47 will occur, thereby energizing the relay coil 40 to close the switch 39 and open the valve member 30. The electrical network including the relay coil 40, tube 47 and cell 44 may be any of the well known systems supplied with alternating current from the usual line voltage transformer 48 and therefore a detailed description of the network is not necessary to a full understanding of this invention. When liquid refrigerant enters the transparent conduit section 16 and refracts the light beam 41 so that it fails to pass through the shield aperture 42, then the electron tube 47 will be deenergized

and the switch 39 will open so that the valve 30 will move quickly to closed position under the force of gravity and spring 32.

The operation of the refrigeration system of Fig. 1 will be apparent from the foregoing, although it may be noted that the system is particularly adapted for use in air conditioning or the like where the load on the evaporator 13 will be maintained substantially constant. At the beginning of a cycle of compressor operation the liquid refrigerant line will have receded toward the header 14 from the conduit section 16 so that the valve 30 will be open and refrigerant will be supplied to the feeding chamber 23 and thence to the evaporator tubes 12. As soon as the liquid refrigerant intercepts the light beam 41 sufficiently to deenergize the cell 44, then the valve 30 will close as above noted. Intermittent opening and closing of the valve 30 will then continue during the compressor operation so that liquid refrigerant will be maintained in the feeding chamber 23 and the evaporator 13 will be refrigerated throughout its length.

Referring to Fig. 2 the electric distributor 8 is controlled by a differential switch 50 having volatile liquid power elements 51, 52 with temperature responsive bulb elements 53, 54 respectively. The power elements 51 and 52 operate to close the switch 50 whenever the difference between their respective temperatures exceeds a predetermined amount, the switch closure energizing the distributor coil 27 so that liquid refrigerant is supplied to the feeding chamber 23 and thence to the evaporator 13. The bulb 53 is clamped to one of the evaporator tubes 12 adjacent its inlet end and the bulb element 54 is clamped to the suction line 15 so that irrespective of the temperature range to which the bulb elements 53 and 54 are subjected, they will function to control the switch solely in accordance with the differential between their temperatures and accordingly will maintain the evaporator 13 completely refrigerated during the compressor operating cycle. The operation of the system of Fig. 1 with the control switch 50 will be apparent from the foregoing description.

Having thus described my invention, what is claimed and is desired to be secured by Letters Patent of the United States is:

1. In a refrigerating apparatus a multi-tube evaporator having a suction header, a tubular vertical housing member, a horizontal partition dividing said housing member internally into an upper inlet chamber and a lower liquid feeding chamber, said partition having a valve port, a casing on the upper end of said housing member, an electro-magnetic coil in said casing, a valve member in said inlet chamber and movable to close and to open said port and having an armature cooperable with said coil, a bottom wall closing the bottom end of said feeding chamber and having a plurality of passageways therethrough leading from said feeding chamber, each of said passageways having a calibrated orifice portion, said port having an effective flow area when said valve member is open which is greater than the combined flow areas of said orifice portions thereby to maintain liquid refrigerant in said feeding chamber, said housing member having an inlet passageway to said inlet chamber, refrigerant feeding tubes connecting said bottom wall passageways to the tubes of said evaporator, and switch means responsive to the extent of refrigeration of said evaporator and controlling said electro-magnetic coil.

2. In a refrigerating apparatus a multi-tube evaporator having a suction header, a tubular vertical housing member, a horizontal partition dividing said housing member internally into an upper inlet chamber and a lower liquid feeding chamber, said partition having a valve port, a casing on the upper end of said housing member, an electro-magnetic coil in said casing, a valve member in said inlet chamber and movable to close and to open said port and having an armature cooperable with said coil, a bottom wall closing the bottom end of said feeding chamber and having a plurality of passageways therethrough leading from said feeding chamber, each of said passageways having a calibrated orifice portion, said port having an effective flow area when said valve member is open which is greater than the combined flow areas of said orifice portions thereby to maintain liquid refrigerant in said feeding chamber, said housing member having an inlet passageway to said inlet chamber, refrigerant feeding tubes connecting said bottom wall passageways to the tubes of said evaporator, a relay switch controlling said electro-magnetic coil, a suction conduit connected to said header, and photo-electric controlling means responsive to predetermined flow of liquid refrigerant into said suction conduit and controlling said relay switch.

3. In a refrigerating apparatus, a plurality of refrigerant evaporating members, a common suction line leading from said members, a housing member having an inlet chamber with an inlet for admission of liquid refrigerant and having a liquid feeding chamber communicating with said inlet chamber through a valve port, a valve member controlling said port and having open and closed positions, electrically operable means to move said valve member quickly from and to said positions, said housing member having a plurality of passageways leading from the bottom of said feeding chamber, each of said passageways having a calibrated orifice portion, said valve port having an effective flow area when said valve member is in said open position which is greater than the combined flow areas of said orifice portions thereby to maintain liquid refrigerant over said passageways and in said feeding chamber, refrigerant feeding tubes connecting said passageways to said evaporating members, and means responsive to a refrigerant condition in said suction line and controlling the energization of said electrically operable means.

4. A liquid refrigerant distributing device, comprising a housing member having an inlet chamber with an inlet for admission of liquid refrigerant and having a liquid feeding chamber communicating with said inlet chamber through a valve port, a valve member controlling said port and having open and closed positions, means to move said valve member quickly from and to said positions, said housing member having a plurality of passageways leading from the bottom of said feeding chamber, each of said passageways having a calibrated orifice portion, said valve port having an effective flow area when said valve member is in said open position which is greater than the combined flow areas of said orifice portions thereby to maintain liquid refrigerant over said passageways and in said feeding chamber.

5. A liquid refrigerant distributing device, comprising a housing member having an inlet chamber with an inlet for admission of liquid refrigerant and having a liquid feeding chamber communicating with said inlet chamber through a

valve port in the top wall of said feeding chamber, a valve member controlling said port and having open and closed positions, electrically operable means to move said valve member quickly from and to said positions, said housing member having a plurality of passageways leading from the bottom of said feeding chamber, each of said passageways having a calibrated orifice portion, said valve port having an effective flow area when said valve member is in said open position which is greater than the combined flow areas of said orifice portions thereby to maintain liquid refrigerant over said passageways and in said feeding chamber.

15 6. A liquid refrigerant distributing device, comprising a housing member having an inlet chamber with an inlet for admission of liquid refrigerant and having a liquid feeding chamber communicating with said inlet chamber through a valve port in the top wall of said feeding chamber, a solenoid operated valve member on the inlet side of and cooperable with said port and having only full open and full closed positions, said housing member having a plurality of passageways leading from the bottom of said feeding chamber, each of said passageways having a calibrated orifice portion, said valve port having an effective flow area when said valve member is in said open position which is greater than the combined flow areas of said orifice portions thereby to maintain liquid refrigerant over said passageways and in said feeding chamber.

20 7. A liquid refrigerant distributing device, comprising a housing member having an inlet chamber with an inlet for admission of liquid refrigerant and having a liquid feeding chamber communicating with said inlet chamber through a valve port, a valve member controlling said port and having open and closed positions, means to move said valve member quickly from and to said positions, said feeding chamber having an open lower end, a closure member for said lower end and sealed to said housing member, said closure member having a plurality of passageways therethrough leading from said feeding chamber, an orifice plate secured to said closure member and having calibrated orifices therethrough registering with said passageways, said valve port having an effective flow area when said valve member is in said open position which is greater than the combined flow areas of said orifice portions thereby to maintain liquid refrigerant over said passageways and in said feeding chamber.

25 8. A liquid refrigerant distributing device, comprising a housing member having an inlet chamber with an inlet for admission of liquid refrigerant and having a liquid feeding chamber communicating with said inlet chamber through a valve port, a valve member controlling said port and having open and closed positions, means to move said valve member quickly from and to said positions, said feeding chamber having an open bottom end, a closure member clamped to said housing member and closing the bottom end of said feeding chamber and having a recess in its chamber face, said recess extending beneath the wall of said housing member, a plurality of passageways extending vertically through said closure member and leading from said recess, an orifice plate fitting said recess and having an edge portion underlying said housing member wall and clamped between said housing member and said closure member, said orifice plate having calibrated orifices therethrough registering

with said passageways, said valve port having an effective flow area when said valve member is in said open position which is greater than the combined flow areas of said orifice portions thereby to maintain liquid refrigerant over said passageways and in said feeding chamber.
